D12-20.

OR D 13,386 EX

No. 13,386

Oct 31, 1882

UNITED STATES PATENT OFFICE.

JOHN L. POPE, OF CLEVELAND, OHIO.

DESIGN FOR A SPRING-SADDLE CLIP-PLATE.

SPECIFICATION forming part of Design No. 13,386, dated October 31, 1882.

Application filed August 2, 1882. Term of patent 7 years.

To all whom it may concern:

Be it known that I, JOHN L. POPE, of Cleveland, in the county of Cuyahoga and State of Ohio, have invented and produced a new and original Design for Spring-Saddle Clip-Plates, of which the following is a specification, reference being had to the accompanying engraving, forming part thereof.

My invention relates to a design for spring-saddle clip-plates; and it consists in certain features of configuration, as will be hereinafter more particularly described and claimed.

In the accompanying engraving the article shown is made up of a long bar portion, *a*, centrally perforated with pointed or spear-shaped ends, and with two cross bars or pieces, *b b*. The bar *a* is made peaked along its upper side or face, is widest at its middle, where the per-

foration occurs, and has its edges run convergently until the inner edges of the cross-bars *b b* are met. The bars *b b* are grooved on top, and are beveled at their edges.

What I claim as my invention, and desire to secure by design Letters Patent, is—

1. A spring-saddle clip plate made up of the bars *a* and *b b*, disposed substantially as shown.
  2. A spring-saddle clip-plate made up of the bars *a* and *b b*, and having substantially the form shown and described.
- In witness whereof I have hereunto set my hand this 17th day of July, 1882.

JOHN L. POPE.

In presence of—

L. S. FISH,
FRANK N. WILCOX.
